UNITED STATES PATENT OFFICE

154,272

DESIGN FOR A TRAY FOR CHILD'S CHAIR

Jacob G. Heim, San Gabriel, Calif.

Application June 16, 1947, Serial No. 139,728

Term of patent 14 years

(Cl. D15—1)

To all whom it may concern:

Be it known that I, Jacob G. Heim, a citizen of the United States, residing at San Gabriel, in the county of Los Angeles and State of California, have invented a new, original, and ornamental Design for Tray for Child's Chair, of which the following is a specification, reference being had to the accompanying drawing, forming part part thereof, in which:

Fig. 1 is a perspective view of a tray for child's chair, showing my new design.

Fig. 2 is a section on a plane represented by the line 2—2 of Fig. 1; and

Fig. 3 is a side elevational view showing my new design.

I claim:

The ornamental design for a tray for child's chair, as shown.

JACOB G. HEIM.
